UNITED STATES PATENT OFFICE.

ALBERT J. ROOSE, OF LAWRENCE, MASSACHUSETTS, ASSIGNOR TO DRAPER CORPORATION, OF HOPEDALE, MASSACHUSETTS, A CORPORATION OF MAINE.

FEELER MECHANISM FOR LOOMS.

Application filed June 19, 1922. Serial No. 569,267.

To all whom it may concern:

Be it known that I, ALBERT J. ROOSE, a subject of the King of Belgium, residing at Lawrence, county of Essex, State of Massachusetts, have invented an Improvement in Feeler Mechanism for Looms, of which the following description, in connection with the accompanying drawing, is a specification, like characters on the drawing representing like parts.

This invention relates to a feeler mechanism for filling replenishing looms for detecting and indicating substantial exhaustion of the filling on the running filling carrier and in which the feeler mechanism is of that type comprising an impinging member and a detecting member preferably in the form of a penetrating member adapted to penetrate the filling mass while the impinging member is adapted to impinge against the filling mass on each detecting beat up of the lay. The detecting or penetrating member thus has no movement with respect to the impinging member so long as there is a working supply of filling on the running filling carrier, but when the filling has run off so that the filling carrier is substantially exhausted the detecting or penetrating member comes into contact with a hard surface of the barrel of the filling carrier and is thus moved with respect to the impinging member and this movement is utilized to initiate filling replenishment.

The object of the present invention is to provide for the protection of the detecting or penetrating member so as to prevent its filling replenishment initiating movement with respect to the impinging member whenever there is an improper presentation of a hard surface opposite the members. Such an improper presentation may occur upon the rebound or mispositioning of the shuttle at the detecting end of the lay whereby the wall of the shuttle or the clamping device in the shuttle for gripping the base of the bobbin or other hard surface is presented opposite the detecting member.

The object of the invention is further and more particularly to provide for the foregoing purpose a protecting projection extending rearwardly from the face of the impinging member above the detecting or penetrating member.

The nature and objects of the invention

will appear more fully from the accompanying description and drawing and will be particularly pointed out in the claims.

In the drawings:

Fig. 1 is a side elevation of a feeler mechanism embodying a preferred form of the invention;

Fig. 2 is a top plan view of the feeler mechanism shown in Fig. 1;

Fig. 3 is a view partially in transverse cross section showing the lay, shuttle and portion of the feeler mechanism with the shuttle improperly positioned on the detecting beat-up.

The feeler mechanism of this invention is particularly designed for use in connection with the well-known Northrop type of automatic filling replenishing loom and as that type of loom is well-known and familiar to those skilled in the art no illustration or description thereof is necessary.

The feeler mechanism itself, except for the novel feature involved in this invention, is also of a type well-known to those skilled in the art. One form of this type of feeler mechanism corresponding closely to that herein illustrated in connection with the present invention is disclosed in the patent to Nichols, 1,380,157 granted May 31, 1921.

In this type of feeler mechanism the feeler stand 1 is secured to the breast beam 2 at the filling detecting side of the loom at a point opposite the base of the barrel of the running filling carrier when the shuttle is boxed at this side of the loom. The feeler slide is mounted for forward and rearward movement in the feeler stand and is shown as comprising a cylindrical stem 3 projecting forwardly from a cross bar 4 and two arms 5 projecting rearwardly from this cross bar. The cross bar 4 and stem 3 are located in the hollow box-like structure of the stand and the stem is surrounded by a helical spring 6 which normally tends to hold the feeler slide yieldingly projected rearwardly.

At their rearward ends the arms 5 of the feeler slide terminate in the impinging member 7.

The detecting member which is shown in the form of a penetrating or needle-like member 8 provided with a sharp or wedge-shaped effective end 9 is mounted to slide forwardly and rearwardly in the impinging member and thus not only has movement

with the impinging member but a movement with respect to the impinging member. It is the latter movement which in this type of feeler mechanism is available of to effect the initiation of filling replenishment. In the construction illustrated the penetrating member is bent upwardly and forwardly at 10 to contact with the head of an adjustable screw 11 carried by the finger 12 pivoted at 10 13 between the side bars 5 of the impinging member. This finger 12 is held in its raised or inactive position and in contact with the forward end of the penetrating member by any suitable means such as the vertical pin 14 pressed upwardly by the helical spring 15.

A controller 16 movable in a guide slot 17 in the feeler stand is connected in a usual and familiar manner with the filling replenishing mechanism. When the finger 12 is in 20 its elevated or inactive position illustrated its path of movement forwardly with the feeler slide is above the controller so that the notched forward end 18 of the finger cannot catch and move the controller as the feeler slide moves forwardly under the impact of the lay and against the tension of the spring 6. But if when this movement of the feeler slide takes place the finger 12 is depressed to bring its notched end 18 opposite the controller 16 then the controller 30 will be caught by the finger and carried forwardly with the feeler slide and effect an initiation of filling replenishment.

The filling carrier is shown in the form 35 of the usual bobbin having the base 19 and barrel 20 and carried and held by the usual clamps 21 in the shuttle 22 which is picked back and forth on the lay 23. At the end of each pick the shuttle enters a shuttle 40 box one wall 24 of which is shown at the detecting end of the lay. The wall 24 of the shuttle box and the adjacent wall of the shuttle 22 are apertured to permit the entrance of the detecting members of the feeler slide into the shuttle.

The operation of this type of feeler mechanism is familiar and in general is as follows. So long as there is a sufficient supply of filling on the running filling carrier 50 when on the beat-up of the lay the filling carrier comes into contact with the feeler, the penetrating member sinks into the mass of filling and the impinging member contacts with the mass of filling. As the beat-up continues the feeler slide moves forwardly but there is no movement of the penetrating member with respect to the impinging member and consequently the notched end 18 of the finger 12 passes over 55 the controller 16. When, however, the filling has become substantially exhausted the surface of the barrel 20 of the filling carrier 60 will contact with the penetrating member pushing it forwardly in and with respect to 65 the impinging member and in turn rocking

the finger 12 to bring its notched end 18 into line with the end of the controller 16. As the beat-up now continues the feeler slide moves forwardly with the parts remaining in this position and the notched end 18 of the finger 12 catching the controller 16 carries it forwardly and initiates filling replenishment.

It will thus be seen that it is important 75 that the detecting or penetrating member 8 shall not be given a movement with respect to the impinging member 7 except when the running filling has become substantially exhausted and the end of the detecting or penetrating member is thus brought into engagement with the hard surface of the barrel 20 of the filling carrier. If, for example, the shuttle rebounds or is mispositioned or improperly boxed at the detecting end of the loom some hard surface such as the wall 80 of the shuttle or the face of the filling carrier clamp 21 may be brought into contact with the end of the detecting or penetrating member and thus improperly effect its movement with respect to the impinging member 90 and thus cause premature initiation of filling replenishment.

The present invention obviates this difficulty by providing on the face of the impinging member a protecting projection extending rearwardly from the face of the impinging member above the detecting member. In the preferred form of the invention this protecting projection is secured by curving the face of the impinging member upwardly and rearwardly from the detecting member to form the protecting projection 25 and this is best effected by curving the face of the impinging member 100 to conform substantially to the opposed surface of the barrel 20 of the filling carrier. 105

It will be understood that the terms "above" and "upwardly" used with respect to the projection 25 in its relation to the penetrating member are terms of relation and not of limitation because it is immaterial whether this projection be above or below the penetrating member. 110

It will thus be seen that this protecting projection 25 whenever there is an improper presentation of a hard surface opposite to the detecting members upon the detecting beat-up will take the blow without effecting movement of the detecting or penetrating member with respect to the impinging member. But if there is no such improper presentation of a hard surface opposite the said members this protecting projection will not interfere with the engagement of the hard surface of the filling carrier barrel 20 to effect movement of the detecting or penetrating member with respect to the impinging member when the running filling is substantially exhausted.

Having thus described my invention, what 130

I claim as new and desire to secure by Letters Patent, is:

1. A feeler mechanism for looms comprising an impinging member adapted to engage and be moved forwardly by the running filling carrier upon a detecting beat, a detecting member movable with and with respect to the impinging member, means actuated by movement of the detecting member with respect to the impinging member followed by forward movement of the detecting member with the impinging member for initiating filling replenishment, the impinging member having a protecting projection extending rearwardly from its face above the detecting member whereby upon the improper presentation of a hard surface opposite the said members upon the detecting beat the blow will be taken by the said projection without effecting movement of the detecting member with respect to the impinging member.
2. A feeler mechanism for looms comprising the construction defined in claim 1 in which the face of the impinging member is curved upwardly and rearwardly from the detecting member in substantial conformity to the surface of the barrel of the filling carrier to form the said protecting projection.
3. A feeler mechanism for looms comprising an impinging member adapted to engage and be moved forwardly by the running fill-

ing carrier upon the detecting beat, a penetrating detecting member having a penetrating portion normally projecting rearwardly beyond the face of the impinging member and movable with and with respect to the impinging member, means actuated by movement of the penetrating member with respect to the impinging member followed by forward movement of the penetrating member with the impinging member for initiating filling replenishment, the impinging member having a protecting projection extending rearwardly from its face above the penetrating member whereby upon the improper presentation of a hard surface opposite said members upon the detecting beat the blow will be taken by the said projection without effecting movement of the penetrating member with respect to the impinging member.

4. A feeler mechanism for looms comprising the construction defined in claim 2 in which the face of the impinging member is curved upwardly and rearwardly from the detecting member in substantial conformity to the surface of the barrel of the filling carrier to form the said protecting projection.

In testimony whereof, I have signed my name to this specification.

ALBERT J. ROOSE.
